LUMBER RULE HEAD

Edward M. Conway, Benjamin F. Smith and Harold E. Hamilton, Grand Rapids, Mich., assignors to Conway Lumber Rule Company, Grand Rapids, Mich., a corporation of Michigan

Filed May 2, 1966, Ser. No. 2,092

Term of patent 14 years

(Cl. D52—6)

FIG. 1.

FIG. 2.

FIG. 3.

FIG. 1 is a front perspective view of a lumber rule head embodying our new design;

FIG. 2 is a rear perspective view thereof; and

FIG. 3 is a rear elevational view thereof.

The characteristic feature of our design resides in the substantially elliptical head with rearwardly extending pointed ends in association with the bifurcated gauging elements as shown.

We claim:

The ornamental design for a lumber rule head, substantially as shown and described.
